CORNER PROTECTOR FOR BINDING STRAPS
SURROUNDING BUNDLES OF SHEETS AND THE LIKE

Bela G. Szabo, Pittsburgh, Pa., assignor to Bruce Plastics, Inc., Pittsburgh, Pa.

Filed May 14, 1971, Ser. No. 143,744

Term of patent 14 years

Int. Cl. D8—99

U.S. Cl. D8—263

Fig. 1.

Fig. 2.

Fig. 3.

Fig. 4.

FIG. 1 is a plan view of the corner protector for binding straps surrounding bundles of sheets and the like;

FIG. 2 is a front elevation thereof;

FIG. 3 is a right end view of FIG. 2; and

FIG. 4 is a perspective view of the corner protector looking at the inner faces thereof.

I claim:

The ornamental design for a corner protector for binding straps surrounding bundles of sheets and the like, as shown.
